HAT SHAPING APPARATUS

Constantine H. Marris, Springfield, N. J.

Application April 28, 1950, Serial No. 158,704

4 Claims. (Cl. 223—12)

1

This invention relates to hat shaping apparatus and more particularly to apparatus for shaping woven fibre hats of the type referred to in the trade as Panama hats.

It is among the objects of the invention to provide improved hat shaping apparatus for initially shaping and sizing woven fibre hats which apparatus is light in weight and fully portable and requires only ordinary house current for its complete operation so that it can be set up for operation in any convenient location and easily moved when desired, which firmly supports a hat during the hat shaping operation so that the hat can be first manually shaped to the desired configuration and then be clamped in shaped and pressed so that it will retain the shape which it has been given, which provides an accurate form or guide for shaping and sizing the hats so that all of the hats shaped thereon will be of uniform shape and size, which materially facilitates and expedites the shaping of hats of the character indicated, and which is simple and durable in construction, economical to manufacture, positive and efficient in operation and easy to use.

Other objects and advantages will become apparent from a consideration of the following description and the appended claims in conjunction with the accompanying drawings wherein:

Figure 1 is a side elevational view of hat shaping apparatus illustrative of the invention;

Figure 2 is a top plan view of the lower unit of the hat shaping apparatus illustrated in Figure 1, looking from the line 2—2 of Figure 1;

Figure 3 is a cross sectional view on the line 3—3 of Figure 1;

Figure 4 is an elevational view on an enlarged scale of a fragmentary portion of the apparatus, a portion of the apparatus fragment shown in elevation being broken away and shown in cross section to better illustrate the construction thereof; and

Figure 5 is an elevational view on an enlarged scale of a fragmentary portion of the apparatus.

With continued reference to the drawings, the apparatus comprises a flat base 10 which may be a base especially provided for the apparatus or may be a table top or other convenient working surface, and a standard 11 secured at one end to the base and upstanding therefrom.

An arm 12 projects laterally from the standard 11 near the end of the standard remote from the base 10 and substantially perpendicular to the standard and a bracket 13 is secured at one end to the arm 12 at a location spaced from the standard 11 and projects from the arm 12 in a

5 direction away from the base 10. An apertured guide structure 14 is secured on the end of the arm 12 remote from the standard 11 and an elongated rack bar 15 extends slidably through the guide structure 14. The rack bar has a series 10 of rack teeth thereon and a gear 17 is journaled on the bracket 13 at the end of the latter remote from the arm 12 and meshes with the series of rack teeth 16 on the rack bar. The gear 17 is secured on a shaft 18 journaled in the bracket 13 and a hand lever 19 is secured at one end to the shaft 18 and projects radially therefrom for rotating the gear to move the rack bar 15 toward and away from the base 10. A clip 20 extends from the bracket 13 and around the rack bar 15 adjacent the gear 17 to retain the rack teeth in mesh with the gear teeth and tension springs 21 are connected each at one end to the gear 17 and at its other end to the arm 18 adjacent the guide structure 14 for rotating the gear in a direction to raise the rack bar after manual pressure on the lever 19 rotating the gear to lower the rack bar has been released. The rack bar is provided intermediate the length 25 thereof with a series of notches or serrations 22 and a latch 23 mounted in the guide structure 14 has one end shaped to engage in the notches 22 to releasably lock the latch bar in lowered position. The latch is urged toward the rack bar by compression spring 24 and may be manually released by a knob 25 secured on the end of the latch opposite the notch engaging end thereof.

30 A crown shaping block 26 is secured on the base adjacent end of the rack bar 15. This block is hollow and is preferably formed of a light weight metal, such as aluminum. A heating element 27 is secured in the block 26 at the end of the block remote from the rack bar 15 and an extension cord 28 is electrically connected to this heating element. An adjustable thermostat 29 is mounted on the crown block and connected into the extension cord 28 to regulate the heating of the crown block by the heating element 27.

35 The crown block 26 and its supporting mechanism constitute an upper unit of the apparatus and the apparatus also includes a lower unit movably mounted on the base 10.

40 The lower unit includes an annular form ring 30, an annular guide ring 31 receivable on the form ring and an annular clamp ring 32 receivable within the guide ring and releasably clamped to the form ring to hold a hat brim on the form ring while the crown of the hat is being formed by the crown block 26.

45 The form ring 30 is a hollow, annular body of

suitable metal, such as aluminum, and has a hat crown receiving opening 33 therein and a hat brim shaping surface 34 convexly curved and surrounding the opening 33 at the side of the form ring remote from the base. An annular heating element 35 is provided within the form ring and embedded in an annular ring 36 of refractory material. The extension cord 28 is branched and connected to the heating element 35 and an adjustable thermostat 37 is mounted on the form ring and connected into the extension cord to control the heating of the form ring by the heating element 35.

An annular extension 37 surrounds and is secured to the form ring at the side of the latter remote from the brim shaping surface 34 and four legs 39 are secured each at one end to the annular extension 37 at angularly spaced apart locations around the latter for supporting the form ring on the base 10. A roller 39 is journaled in the end of each leg remote from the form ring so that the form ring can be easily moved from a position on the base in which it is directly below the crown block 26 to some other position in which it is more accessible for manually shaping a hat supported on the form block.

The guide ring 31 surrounds the form block substantially parallel to the extension 37 and this ring is secured to the extension 37 by adjustable means such as the screws 40 which extend through apertures in the extension 37 at angularly spaced apart locations therearound and are adjustably threaded into tapped holes 41 provided in the guide ring 31. A compression spring 42 surrounds each pin 40 between the extension 31 of the form block and the guide ring 31, the ends of these springs being received in counterbores provided in the form ring extension and the guide ring, and each screw is provided on its end remote from the guide ring with a head 43 which is engageable with the adjacent surface of the form ring extension to prevent separation of the guide ring from the form ring while permitting the guide ring to move relative to the form ring toward and away from the base 10.

Hooks 44 pivotally connected to the guide ring 31 are engageable with pins 45 projecting out from the form ring extension 37 to releasably latch the guide ring in position relative to the form ring such that the side of the guide ring remote from the form ring extension 37 is substantially flush with the brim forming surface 34 of the form ring.

With the guide ring latched down by the hooks 44, a hat blank may be placed in the form ring and manually worked until its crown fits the crown receiving opening in the form ring and its brim covers the brim forming surface 34 of the form ring. The hooks 44 may then be released and the guide ring will be raised by the springs 42 until it extends above the brim forming surface 34 at which time the brim may be further worked until its edge contacts the guide ring entirely around the edge of the brim forming surface of the form ring.

The guide ring 31 is preferably provided as a solid body of suitable metal, such as aluminum, and this ring has an internal annular groove 46 which is flush with the outer edge of the brim forming surface 34 when the hooks 44 are released and the heads 43 of the screw 40 are disposed against the adjacent surface of the form ring extension 37. When the guide ring is in this last described position the edge of the hat brim

may be forced outwardly into the groove 46 and this groove accurately shapes the outer edge of the hat brim.

After the hat brim has been shaped onto the form ring 30 the clamp ring 32 is clamped down onto the portion of the hat brim adjacent the guide ring 31 to hold the brim firmly in shape while the crown of the hat is being shaped.

The clamp ring 32 is a solid body of annular shape formed of a suitable metal, such as aluminum, and is dimensioned so that its fits closely into the guide ring 31. The edge of the clamp ring adjacent the form ring is shaped to provide a concave surface complementary to the edge or marginal portion of the convex brim forming surface 34 and this ring is provided at its opposite edge with lifting handles 47 for removing the clamp ring from the form ring and guide ring assembly.

Two brackets 48 and 49 are secured to the form ring extension 31 at respectively opposite sides of the form ring and extend from the form ring extension 31 past the guide ring 31. An arm 50 is pivotally connected at one end to the bracket 48 at the end of the latter remote from the extension 37 and a corresponding arm 51 is pivotally connected to the bracket 49. These arms are of a length such that their free or distal ends overlie the upper edge of the clamp ring 32 and they are provided near such free or distal ends with bolts 52 and 53 respectively which provide adjustable abutments carried by the arms and engaging the clamp ring.

A U-shaped handle 54 is pivotally connected at its open end to the bracket 48 adjacent the pivotal connection between this bracket and the arm 50 and a similar handle 55 is connected to the bracket 49. A link structure 56 is connected between the handle 54 and the arm 50 and is provided with a stop formation 57 engageable with the arm to hold the handle in a position in which it forces the abutment 52 on the distal end of the arm 50 downwardly on the clamp ring 32. A similar link structure 58 is connected between the handle 55 and the arm 51.

After the hat brim has been shaped to the form block 30, the clamp ring 32 is placed on the hat brim and within the guide ring 31 and the handles 54 and 55 are then moved relatively toward each other to force the clamp ring toward the form ring and clamp the marginal portion of the hat brim firmly in position.

The lower unit comprising the rings 30, 31 and 32 is then moved under the crown block 26 and the crown block is lowered by the handle 19 into the crown of the hat to shape the latter. The hat will be thoroughly wet when placed in the shaping apparatus and the heat provided by the heating elements in the form ring and crown block will dry the hat while the hat is held in properly shaped condition so that the hat will tend to retain the given shape after it has been removed from the apparatus.

The crown block is held in position in the crown of the hat by the latch 23 and in order to remove the hat from the apparatus this latch is released by the knob 25 permitting the springs 21 to raise the crown block. If necessary, the springs may be assisted by an upward lift on the distal end of the hand lever 19. After the crown block has been raised the lower unit is pulled out from under the crown block to a position convenient to the operator and the handles 54 and 55 are then moved to release the clamp ring 32. The clamp ring 32 is then removed from

the assembly by the handles 47 and the shaped hat may then be lifted from the form ring 30 and replaced by a new blank.

When the hats have been shaped and sized on the apparatus of the present invention they are ready to be placed in a hydraulic shaping press to give them their permanent shape and finish.

The invention may be embodied in other specific forms without departing from the spirit or essential characteristics thereof. The present embodiment is, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

What is claimed is:

1. Hat shaping apparatus comprising a base, a form ring movably supported on said base and having a hat crown receiving opening therein and a brim shaping surface surrounding such opening, a heating element in said form ring, a guide ring surrounding said form ring and movably connected to the latter for movement toward and away from said base, said guide ring being movable to a position in which it projects beyond said brim shaping surface to constitute a guide for the edge of the brim of a hat being shaped on the apparatus, a clamping ring disposable within said guide ring to clamp a hat brim on said brim shaping surface, releasable clamps carried by said form ring and engageable with said clamping ring to clamp a hat brim between said clamping ring and said form ring, a standard secured at one end to said base, an arm projecting laterally from said standard, a rack slidably mounted on said arm at a location spaced from said standard, a crown block secured on the base adjacent end of said rack and receivable in the crown receiving opening in said form ring when the latter is supported on said base directly below said crown block, a heating element in said crown block, and manually operated means carried by said arm and engaging said rack to move said crown block into and out of the crown receiving opening in said form ring.

2. Hat shaping apparatus comprising a base, a lower unit movably supported on said base and arranged to clamp a hat blank therein, and an upper unit mounted on said base and including a crown shaping block movable into said lower unit to shape a hat blank clamped in the latter, said lower unit comprising an annular form ring having a hat crown receiving opening therein and a brim receiving surface surrounding said opening, means extending from the side of said form ring remote from said brim receiving surface to support said lower unit on said base, a guide ring mounted on said form ring and surrounding said brim receiving surface, a clamp

ring disposed within said guide ring in opposition to said brim receiving surface, and clamp means carried by said form ring and engageable with said clamp ring to force the latter toward said brim receiving surface for clamping a hat brim between said form ring and said clamp ring.

3. Hat shaping apparatus comprising a base, a lower unit movably supported on said base and arranged to clamp a hat blank therein, and an upper unit mounted on said base and including a crown shaping block movable into said lower unit to shape a hat blank clamped in the latter, said lower unit comprising an annular form ring having a hat crown receiving opening therein and a brim receiving surface surrounding said opening, means extending from the side of said form ring remote from said brim receiving surface to support said lower unit on said base, a guide ring mounted on said form ring and surrounding said brim receiving surface, a clamp ring disposed within said guide ring in opposition to said brim receiving surface, and clamp means carried by said form ring and engageable with said clamp ring to force the latter toward said brim receiving surface for clamping a hat brim between said form ring and said clamp ring, said guide ring having an annular groove therein for receiving the edge of a hat brim, and means connecting said guide ring to said form ring for positioning said groove in registry with the outer edge of said brim receiving surface.

4. A hat shaping assembly comprising a first ring having a hat crown receiving opening therein and a convexly curved brim receiving surface surrounding said opening at one side of said first ring, means secured to said first ring and projecting from the opposite side thereof for supporting said assembly on a base, a second ring surrounding the brim receiving surface of said first ring to constitute a guide for properly shaping the edge of a hat brim, adjustable means connecting said second ring to said first ring for movement of said second ring relative to said first ring between positions in which said second ring is substantially flush with said brim receiving surface and in which said second ring projects beyond said brim receiving surface, a third ring received in said second ring, and clamp means carried by said first ring and engageable with said third ring to clamp a hat brim between said third ring and said brim receiving surface.
